CLAIM

The ornamental design for a pendent enclosure for
electrical devices such as push button switches, substan-
tially as shown and described.

DESCRIPTION

FIG. 1 is a perspective view of a pendent enclosure for
electrical devices such as push button switches showing
my new design;

FIG. 2 is a front elevational view thereof on a smaller
scale than FIG. 1;

FIG. 3 is a view in side elevation of one side thereof, the
other side of the pendent enclosure being the same but
reversed;

FIG. 4 is a rear elevational view thereof;

FIG. 5 is a top plan view thereof;

FIG. 6 is a bottom plan view thereof;

FIG. 7 is a front elevational view of a pendent enclosure
similar to the FIG. 1 pendent enclosure but of increased
width for mounting two columns of electrical devices
such as push button switches;

FIG. 8 is a rear elevational view of the FIG. 7 pendent
enclosure;

FIG. 9 is a top plan view of the FIG. 7 pendent enclo-
sure;

FIG. 10 is a bottom plan view of the FIG. 7 pendent
enclosure.

The side elevation of one side of the FIG. 7 pendent
enclosure is the same as shown in FIG. 3, and the side
elevation of the other side thereof is the same as shown
in FIG. 3 but reversed.
